UNITED STATES PATENT OFFICE.

THOMAS BYRNE, JR., OF CHICAGO, ILLINOIS.

CONCRETE MIXER.

Application filed December 27, 1920. Serial No. 433,180.

To all whom it may concern:

Be it known that I, THOMAS BYRNE, Jr., a citizen of the United States, residing at 358 East 115th St., Chicago, in the county 5 of Cook and State of Illinois, have invented a new and useful Improvement in Concrete Mixers, of which the following is a specification.

This invention relates to concrete mixers 10 of the general type using a rotating drum for mixing the component parts of the concrete mixture. One of the features of the invention is to provide a concrete mixer of large capacity, adapted for use at high 15 speed, which will require a minimum of space. The mixers heretofore used, in most cases, require considerable space at one side of the rotating drum in order to accommodate the wheelbarrows or cars which are 20 used for carrying materials to the mixing drum, and also to accommodate a chute or other means which is used for loading materials from the cars or wheelbarrows into the drum. In the devices heretofore 25 used, in most cases, the mixing drum is provided with a pivoted chute projecting from one side of the drum and adapted to be raised or lowered. The chute is lowered, filled with materials from the wheelbarrows 30 or cars, and then raised to cause the materials to flow into the drum. It is obvious that such devices require a considerable space at one side of the drum to accommodate this swinging chute and also the 35 wheelbarrows and cars. Such devices therefore can not be used where the space is narrow as is frequently encountered in cases where the concrete is to be furnished for building a new sewer in a street excavation, 40 and where the mixer must be located in the space between the excavation in the center of the street and the sidewalk at the side which space is frequently very narrow. Thus in the mixing and depositing in place of the 45 concrete employed as the filling between street railway tracks the concrete mixers as at present employed block the space between the outer tracks and the adjacent curb, thus causing a congestion of traffic, or necessitating 50 the detour thereof. In my improved device the mixer may be located on a very narrow strip since no space at the side is required for unloading chute or for cars or wheelbarrows carrying materials. I 55 accomplish this object of my invention by con-

structing the device so that the cars carrying material thereto are conveyed up on top of the mixing drums from which position the materials are dumped into the drums. Because of this construction no loading 60 space at the side is required. This construction will be explained more in detail hereinafter.

Another object of my invention is to provide a device which may be readily moved 65 from one position to another, and which may readily be firmly and rigidly held in place in any desired location.

In that form of device shown in the accompanying drawings, Figure 1 is a view 70 in side elevation, Fig. 2 is a top plan view, Fig. 3 is a fragmentary view similar to Fig. 1 on an enlarged scale, Fig. 4 is a continuation of Fig. 3, Fig. 5 is a view taken as indicated by the line 5 of Fig. 1, Fig. 6 is a 75 view taken as indicated by the line 6 of Fig. 3, Fig. 7 is a view taken as indicated by the line 7 of Fig. 3, Fig. 8 is a view in elevation and of a portion of the conveying chain, and Fig. 9 is a top plan view of Fig. 8. 80

As shown in said drawings, the device comprises, in general, a rigid structure formed of channel irons, with suitable struts and braces. Such frame is composed primarily of two parallel bottom frame members or sills 10 each of which supports at its center three vertical uprights 11. The uprights 11 at about their center points support the horizontal members 12. At one side is arranged two inclined channel irons 14 85 connecting the ends of the horizontal members 12 to the ends of the sills 10. The inclined members 14 support the discharge track 16. Likewise, inclined channels 17 are arranged on the other side to support the receiving track 18. The horizontal members 12 support a platform upon which is mounted the track 19 which joins the receiving track with the discharge track. To one side of the track 19 is arranged a platform 20 for 90 100 the accommodation of an operator.

Mounted on the sills 10, below the members 12, and between the uprights 11, are two rotatable cylindrical mixing drums 23 which may be of any desired construction. 105 As here shown the mixing drums 23 are mounted on the supporting rollers 24 adapted to be driven by the motors 25 through the pinions 26 and 27, or in any other desired manner. The details of the 110

manner of causing rotation of the drums 23, and the details of construction of the drums themselves form no part of the present invention, as drums of the type shown herein 5 are well known in the art.

The entire structure is supported on railway trucks 30 provided with flanged wheels adapted to ride on wide gage rails 32, for the purpose of moving the device from one 10 location to another. Between the rails 32 there is provided an additional rail 32^a to form a pair of rails of narrow gage the same as the gage of the tracks 16, 19 and 18 on the structure.

15 The device is provided with a continuous chain 35, mounted between the rails of the discharge track 16, receiving track 18, and track 19 joining the two. The chain 35 is supported between the rails in a suitable 20 guiding channel 36 and is looped at one end of the device over the driving sprocket 37 and at the other end over an idler wheel 38. The chain 35 leads from the driving sprocket 37 at the lower end of the discharge track 25 16 upwardly between the rails of the discharge track, between the rails of the track 19, downwardly between the rails of the receiving track 18 over the idler wheel 38 at the lower end of the receiving track 18, and 30 thence back along the underside of the device where its slack is supported by the guiding strip 39. The chain 35 is provided with upwardly extending dogs or lugs 40 adapted to engage with the axles 41 of cars 35 42 which carry materials to the mixing drums 23. The chain 35 is adapted to be driven by a motor 45 which drives the driving sprocket 37. Any suitable means for connecting the motor 45 to the driving 40 sprocket 37 may be employed. As shown in the drawings I have provided a bevel gear 46 at the end of the shaft supporting the driving sprocket 37. The bevel gear 46 is adapted to be driven by the bevel gear 47 45 mounted on the shaft 48 which carries the pinion 49 adapted to be driven by a worm mounted on the shaft 50 which in turn carries a pinion 61 meshing with a pinion 52 on the end of the motor shaft. A suitable 50 clutch 54 of any desired form adapted to be operated by the lever 55 is provided for the purpose of disconnecting power from the motor 45. The chain 35 is adapted to be driven in a direction to carry the cars 42 55 up the receiving track 18 across the track 19 and thence down the discharge track 16. Short rail sections 63 are provided at the receiving end of the device for the purpose of affording a connection between the receiving track 18 and the rails 32 and 32^a. The track sections 63 are pivoted at 64 and adapted to be raised and folded out of the way when the structure is being moved. Likewise, short rail sections 60 are provided 60 65 at the discharge end for connecting the dis-

charge rails 16 with the rails 32 and 32^a. The track sections 60 are likewise pivoted at 61.

Means for moving the entire structure on the rails 32 are provided as follows. The 70 shaft 48 is provided with a slidable clutch member 70 adapted to be moved by the operating lever 71 and brought into engagement with the co-acting clutch member 72 which is provided with a bevel gear 73 75 adapted to mesh with the bevel gear 74 mounted on the shaft 75 which carries the driving sprocket 76. The clutch member 70 is splined on the shaft 48 or otherwise arranged in order to be non-rotatable upon 80 said shaft. The driving sprocket 76 is adapted to drive the wheels 79 on one of the trucks 30 by means of the chain 77 acting on the sprocket 78 mounted on the axle 80 which joins the wheels 79. 85

Each of the mixing drums is provided with a funnel shaped feeding hopper 85 adapted to receive the contents of a car 42 dumped therein, and feed the same into the mixing drum. Any suitable kind of dump car 42 may be provided for conveying materials to the hoppers 85. 90

Each of the mixing drums 23 is provided with a discharge chute 87 in which the concrete mixture is discharged from the drum 95 after it has been mixed therein, to the work, or to other conveying mechanism. A short pivoted discharge chute section or gate 88 is also provided in connection with each of the mixing drums 23 to prevent the contents from flowing out before the mixing process has been completed. A discharge chute section 88 may be of any desired form and so constructed that in one position it will hold the contents in its corresponding 100 drum while the mixing is going on, and in another position will permit the contents of a drum to flow from the drum into the discharge chute 87. As here shown, the section 88 is pivoted at 89 and when in the position shown in Fig. 6 will prevent the contents of the drum 23 from flowing out. When it is desired that the contents of the drum 23 flow into the chute 87, the section 88 is pivoted at 89 so that its outer end will 105 110 be lowered and rest in the chute 87, and its inner side correspondingly raised. The details of construction and operation of the feed chute form no part of the present invention, as there are various forms of such 115 feed chutes well known in the art. 120

Near its center the structure is provided with suitable lifting screws 91 adapted to be screwed down to give the structure a firm support on suitable surfaces or blocking 92 125 in order to give greater rigidity and stability to the device, and prevent movement of it, in any desired location.

In the operation of the device, the two rails 32, and the center rail 32^a are laid parallel 130

to the course of work where concrete will be required. The entire structure is then moved to the desired location on the tracks 32 as hereinbefore described. The screws 91 are 5 then screwed down onto suitable blocking or supporting surfaces 92 in order to make the apparatus rigid and stable and prevent movement. The track sections 60 and 63 are then put into place in order to form 10 connections with the rails 32 and 32^a as described above. Rotation of the mixing drums 23 is then commenced by means of the motors 25, and materials are conveyed to the apparatus in the dump cars 42 on the rails 32 and 32^a. Movement of the chain 35 is then 15 commenced by means by the motor 45 as explained above. The cars 42 are then pushed by hand, or in any other suitable manner up the track sections 63 until the 20 dogs 40 on the chain 35 engage with their axles, whereupon they will be carried up the receiving track 18 and onto the track 19. When a car 42 reaches a point opposite and above one of the hoppers 85 in which it is 25 desired to dump the contents thereof, the chain 35 is stopped by disconnecting the power from the motor 45 by means of the clutch 54, and the contents of the car is dumped into the hopper. This dumping may 30 be done, if desired, by an operator standing on the platform 20. The contents of the car 42 is discharged from the hopper 85 into the corresponding mixing drum 23 where it is allowed to churn until thoroughly mixed, 35 when the discharge chute section 88 is moved to a position, as described above, so that the contents of the drum will flow out into the discharge chute 87, and thence conveyed to the work. Either one of the mixing drums 40 23 may be used alone, or they may be used simultaneously. If one is used at a time, the other may be held in reserve, so that the work may be continued if the first should be rendered inoperative. After the contents 45 of the cars 42 are dumped into the hoppers 85 the movement of the chain 35 is again commenced and the car is moved ahead to allow the next one in turn to be moved to dumping position and the cars are then con- 50 veyed down the discharge track 16 until their axles become disengaged from the dogs 40 at the bottom, whereupon they will ride over the track sections 60 again onto the rails 32 and 32^a whence they may be taken 55 away to be refilled.

While I have shown and described certain embodiments of my invention, it is to be understood that it is capable of many modifications. Changes therefore in the construction and arrangement may be made 60 without departing from the spirit and scope of the invention as disclosed in the appended claims, in which it is my intention to claim all novelty inherent in my invention as broadly as possible in view of the prior art. 65

What I claim as new, and desire to secure by Letters Patent is:

1. In a portable concrete mixing apparatus adapted for use in parallelism with and closely adjacent the desired line of deposit of the mixed material, a framing, a mixing drum, a track above said drum adapted to support material supplying cars, an inclined receiving track extending from one end of said first named track, and an inclined discharge track extending from the opposite end of said first named track, all carried by said frame whereby to be moved therewith to different points along the line 70 of the work, for the purpose specified. 75

2. In a portable concrete mixing apparatus adapted for use in parallelism with and closely adjacent the desired line of deposit of the mixed material, a framing, a mixing drum, a feed hopper having an elevated mouth, an elevated track arranged adjacent the mouth of said feed hopper, an inclined receiving track and an inclined discharge track, all carried by said frame whereby to 80 85 90 be moved therewith to different parts along the line of the work, for the purpose specified.

3. In a portable concrete mixing apparatus adapted for use in parallelism with and closely adjacent the desired line of deposit of the mixed material, a framing, a mixing drum, a feed hopper having an elevated mouth, an elevated track arranged adjacent the mouth of said feed hopper, an inclined receiving track and an inclined discharge track, and means for carrying cars up said inclined receiving track to said elevated track, all carried by said frame whereby to be moved therewith to different points along 95 100 105 the line of work, for the purpose specified.

In witness whereof, I have hereunto set my hand and seal this 14th day of October, 1920.

THOMAS BYRNE, JR. [L.S.]
